ATTORNEY

WITNESS:

UNITED STATES PATENT OFFICE.

RUSSELL H. BREMER, OF READING, PENNSYLVANIA, ASSIGNOR OF ONE-THIRD TO
GEORGE H. RICE, OF ARLINGTON, VERMONT.

REFRIGERATOR.

1,408,260.

Specification of Letters Patent. Patented Feb. 28, 1922.

Application filed December 7, 1921. Serial No. 520,645.

To all whom it may concern:

Be it known that I, RUSSELL H. BREMER, a citizen of the United States, residing at Reading, in the county of Berks and State of Pennsylvania, have invented new and useful Improvements in Refrigerators, of which the following is a specification.

This invention relates to refrigerators and has for an object the provision of means 10 for holding ice in a manner to protect the same from direct contact with air and to so locate and arrange the ice compartment as to insure proper distribution of cold air to the contents of the food chamber of the 15 refrigerator.

Another object of the invention is the provision of novel air circulating means, wherein air is admitted to the refrigerator to be acted upon and cooled by the ice without 20 contact with the latter and directed into the food chamber and thus provide a maximum cooling effect with a minimum amount of ice.

With the above and other objects in view, 25 the invention further includes the following novel features and details of construction, to be hereinafter more fully described, illustrated in the accompanying drawings and pointed out in the appended claims.

30 In the drawings:—

Figure 1 is a perspective view of a refrigerator constructed in accordance with the invention, the view being partly broken away and shown in section to more clearly 35 illustrate the invention.

Figure 2 is a vertical sectional view of the same.

Referring in detail to the drawings, wherein like characters of reference denote corresponding parts, the refrigerator is shown as 40 including a casing 10, which may be of any suitable construction and which if desired, may be formed of suitable insulating walls, as is common in devices of this character.

45 Located within the casing is a partition which includes a vertical wall 11 and a horizontal wall 12, the first mentioned wall being spaced from the rear wall of the refrigerator casing and the last mentioned 50 wall spaced from the bottom wall of said casing and extending forwardly from the bottom of the rear wall 11 and providing a food compartment 13. Access to the food compartment 13 is had through the medium

of bores 14, which are shown as located in 55 the front wall of the casing 10.

Located within the refrigerator casing between the rear and bottom walls of the latter and the partition walls 11 and 12, is an ice compartment 15. This compartment is substantially L-shaped and is formed of spaced 60 walls 16 and 17, which are spaced from the casing and partition walls, the space between the partition walls and the walls 17 defining an air passage 18. The ice compartment 15 is open at its top and is adapted to be closed by a suitable cover or closure 19.

The air passage 18 is in communication with the atmosphere through the medium of restricted openings 20, while the partition 70 walls 11 and 12 are provided with openings 21 to establish communication between the air passage 18 and the interior of the food compartment 13.

In the use of the refrigerator, the compartment 15 is filled with ice and the cover or closure 19 positioned to close its upper end. Air entering through the openings 20 will circulate through the air passage 18 against the walls 17 of the ice compartment 80 and will be converted into a frost, so that cold air will enter and circulate through the openings 21 into the food chamber 13. The circulation of air is thus established through the refrigerator, to be acted upon by the 85 ice without coming in contact with the latter, so that the said ice will last for a relatively long period.

A drain pipe 22 extends downward from the ice compartment 15 and may lead to a 90 sewer or drain. This pipe is provided with a valve 23, which is controlled by an operating lever or handle 24, having connection with the valve by means of a rod 25. Excess accumulation of water within the ice compartment 15 may thus be prevented.

The invention is susceptible of various changes in its form, proportions and minor details of construction and the right is herein reserved to make such changes as properly fall within the scope of the appended claims.

Having described the invention what is claimed is:—

1. A refrigerator embodying a casing, a partition spaced from the walls of the casing 105 and having openings therein and providing a food chamber, an ice compartment located between and spaced from the walls of the

food chamber and casing and providing an air circulating passage between said food chamber and ice compartment, said ice compartment having a filling opening therein,
5 a closure for the opening and means whereby air may be admitted to the air passage.

2. A refrigerator embodying a casing, a partition spaced from the walls of the casing and having openings therein and providing
10 a food chamber, a substantially L-shaped ice compartment open at the top and extending along the rear and bottom of the casing be-

tween the said casing and food compartment, the walls of the ice compartment being spaced from the walls of the casing and the 15 walls of the food chamber and providing an air circulating passage along the bottom and rear walls of the food chamber and communicating with the latter through the partition openings and the front portion of the 20 air passage having restricted openings therein for the admission of air.

In testimony whereof I affix my signature.
RUSSELL H. BREMER,
